UNITED STATES PATENT OFFICE.

ERASTUS E. WINKLEY, OF LYNN, MASSACHUSETTS.

MACHINE FOR INSERTING FASTENERS.

1,125,620.

Specification of Letters Patent.

Patented Jan. 19, 1915.

Original application filed December 14, 1908, Serial No. 467,414. Divided and this application filed November 18, 1911, Serial No. 661,150. Renewed May 11, 1914. Serial No. 837,647.

To all whom it may concern:

Be it known that I, ERASTUS E. WINKLEY, a citizen of the United States, residing at Lynn, in the county of Essex and State 5 of Massachusetts, have invented certain new and useful Improvements in Machines for Inserting Fasteners; and I do hereby declare the following to be a full, clear, and exact description of the invention, such as 10 will enable others skilled in the art to which it appertains to make and use the same.

This invention relates to machines for inserting fasteners and more particularly to mechanism for controlling the delivery of 15 such fasteners to the fastener inserting means.

The object of the invention is to provide means in a machine for inserting fasteners, for automatically selecting fasteners of different style or size to be inserted in the 20 work, and, at times to prevent the delivery of fasteners.

Broadly stated, the invention may be embodied in any type of machine which includes fastener inserting mechanism, a plurality of sources of fastener supply therefore, and means for presenting fasteners from the sources of supply to a fastener receiver operatively associated with the inserting mechanism, the presenting means and the receiver being relatively movable, all of which is old, in combination with automatic means controlling the movement of one of the relatively movable parts, preferably said 30 presenting means. It is obvious that with such a construction, the means for controlling the presentation of fasteners to the inserting mechanism is entirely independent of the construction or nature of the source 35 of fastener supply used and therefore may readily be combined with the source of supply of any machine of the general type described.

As is well known to those skilled in the 40 art, in the lasting operation long tacks are used at the toe of the shoe where the upper is more or less folded and short tacks are used at the sides of the shoe where the upper is laid flat. The tacks are presented to the

inserting means by a raceway pivotally mounted on the tack pot and having two roadways carrying respectively long and short tacks. In machines of the prior art the raceway may be shifted by the operator to bring either one of its roadways into position to deliver tacks to the driver, or it may be brought to an inoperative position where it will not deliver tacks to the driver.

In the best form of the invention at present known to the inventor, as applied to a lasting machine, the means for shifting the raceway comprises a cam, continuously rotated from the main shaft, having suitable connections by which it moves the raceway to bring one or the other of the two roadways, or delivery chutes, into proper position to deliver tacks to the tack driving mechanism. When it is desired to prevent the delivery of tacks, the raceway is shifted so that neither one of its delivery chutes is in position to deliver tacks to the tack driving mechanism.

The invention will be best understood from a description of one embodiment thereof, such, for instance, as is shown in the accompanying drawings, in which the invention is shown as applied to the lasting machine illustrated and described in the inventor's co-pending application, Serial No. 467,414 filed December 14, 1908, from which the present application has been divided.

The invention is illustrated as applied to a machine of the type known as the "hand method" lasting machine wherein a single pair of pincers works the upper over the last, after which it is secured to the last by tacks. It is to be understood, however, that the invention is not limited to use with a lasting machine, which is taken as an example of the general type hereinbefore described, nor is it limited to the particular form of fastener, in this instance tacks, illustrated and described.

The preferred embodiment of the invention is illustrated in the accompanying drawings, in which;

Figure 1 is a side elevation of a lasting machine head; Fig. 2 is a section on the line

2—2 of Fig. 1; and Fig. 3 is a detail plan showing particularly the means for automatically shifting the raceways.

The lasting head is of the type commonly known as the consolidated hand method or "nigger head," the general construction of which is fully described and illustrated in the United States patents to Ladd and McFeely, 584,744, June 15, 1897; S. W. Ladd, 10 597,321, January 11, 1898, and J. Cavanagh, Jr., 873,018, December 10, 1907. The machine is caused to perform its lasting and tacking operations by means of the continuously rotating machine shaft O which 15 may be driven from any suitable source of power. A full description of the construction and operation of the lasting instrumentalities may be had by reference to the above mentioned patents.

20 The mechanism for shifting the raceway is actuated by a cam 309, which is continuously rotated by suitable connections to the main shaft O of the lasting head. The cam 309 is mounted upon the rear face of a worm gear 289 carried by a counter shaft 288. The counter shaft is journaled in suitable bearings rising from the lasting head support. The worm gear 289 is engaged by a worm 290 (Fig. 2) on a vertical shaft 291, 25 journaled in bearings 291 sustained by the lasting head frame. The shaft 291 is connected to the shaft O by spiral gears 292 and 293, the latter being the spiral gear shown on the main shaft of the patents hereinbefore referred to.

30

As is usual in lasting machines of this type, the lasting head is provided with a raceway 295 for supplying different size tacks to the driver. This raceway in its 40 construction and mounting is similar to the tack raceway shown in the patent to S. W. Ladd, No. 696,740 of April 1, 1902, which is provided with a pair of roadways for supplying long and short tacks. Like the construction of the patent referred to, the lower end of the raceway 295 is connected by 45 means of a link 296, to a mechanism for shifting the raceway to a position to supply either the long or the short tacks to the driver. This operating mechanism as shown 50 in the present invention, differs from that shown in the patent referred to inasmuch as it is automatic instead of being under the control of the operator. The outer end of 55 the link 296 is forked (Fig. 3) and embraces a pin 297 which is journaled in a suitable bearing 298 sustained in a bracket 299 secured to the lasting head frame. The pin 297 rises from a block 300 (Fig. 1) at the 60 lower side of the bearing 298. Above the fork of the link 296 the pin has secured thereto a disk 301 provided with a slot 301^a which is cut eccentric to the pin 297. This slot is engaged by a small pin 302 which

projects upwardly from the link 296. The 65 forks of the link 296 are mounted for a sliding motion between the under side of the disk 301 and the bearing 298. Rotary motion is imparted to the block 300 through a link, or draw rod, 303 connected at one end 70 to a crank arm 304 projecting from the block and at its other end to the outer end of a lever 305 fulcrumed by its inner end on a pin 306 in a bearing 307 carried on the lasting head frame. The lever 305 is provided with a cam roll 308 between its ends, 75 which is engaged by the cam 309. The cam roll is maintained in contact with its cam by means of a coiled spring 310 secured at one end to the lever 305 and at its other 80 end to the stationary frame work.

The cam 309 is so designed that at the time the toe and heel are being lasted, the lever 305 is moved by the cam in a direction to rotate the block 300 and through the pin 85 and slot connection 301^a and 302 to move the link 296 so as to place the roadway which supplies long tacks in a position to deliver its tacks to the tack carrier. The cam also controls the position of the roadway so that 90 while the sides of the shoe are being lasted, the roadway which supplies short tacks is in a position to supply its tacks to the tack carrier. At certain times in the lasting operation, the roadway should be in a position 95 so that neither of its roadways can supply tacks to the tack carrier. To this end, the cam 309 is so designed that at the desired times a sufficient movement is imparted to the link 296 to place the roadway in a position 100 so that neither of its roadways can supply tacks to the tack carrier. It is apparent that the supply of tacks delivered to the tack driver is thus automatically 105 changed from one side to the other at the proper times as the lasting operation progresses about the periphery of the shoe, and that the delivery of tacks to the driving mechanism and their subsequent waste when it is not desired to drive them in the last is 110 avoided.

While the particulars of construction herein set forth are well suited to one form of the invention, it is not to be understood that these particulars are essential, since they 115 may be variously modified within the skill of the artisan without departing from the true scope of the actual invention as defined in the appended claims.

What is claimed as new is:—

1. A machine for inserting fasteners having, in combination, a driver, mechanism for delivering different sized tacks to said driver, and automatic means for determining the size tack to be delivered, said means 125 being constructed and arranged to wholly prevent the delivery of tacks at predetermined times, substantially as described.

2. A machine for inserting fasteners having, in combination, a driver, a raceway provided with a pair of roadways, a draw rod, means connecting said draw rod and raceways, a cam for operating said draw rod constructed and arranged to permit a delivery from either roadway, and to, at times,

prevent a delivery from both roadways, and means for operating said cam, substantially as described.

ERASTUS E. WINKLEY.
